UNITED STATES PATENT OFFICE

153,907

DESIGN FOR A DOUBLE ACTING SINK VALVE
FAUCET UNIT

Michael Smolensky, Cleveland, Ohio

Application August 1, 1947, Serial No. 140,661

Term of patent 14 years

(Cl. D91—3)

To all whom it may concern:

Be it known that I, Michael Smolensky, a citizen of the United States, residing at Cleveland, in the county of Cuyahoga and State of Ohio, have invented a new, original, and ornamental Design for a Double Acting Sink Valve Faucet Unit, of which the following is a specification, reference being had to the accompanying drawing, forming part thereof.

The single figure of the drawing is a perspective view showing my new design of a double acting sink valve faucet unit.

I claim:

The ornamental design for a double acting sink valve faucet unit, as shown.

MICHAEL SMOLENSKY.
